UNITED STATES PATENT OFFICE.

NEHEMIAH H. CLARK, OF SAN FRANCISCO, CALIFORNIA.

LACING-HOOK FOR WOMEN'S SHOES OR THE LIKE.

SPECIFICATION forming part of Letters Patent No. 709,534, dated September 23, 1902.

Application filed February 12, 1902. Serial No. 93,801. (No model.)

To all whom it may concern:

Be it known that I, NEHEMIAH H. CLARK, a citizen of the United States, residing at San Francisco, in the county of San Francisco and 5 State of California, have invented certain new and useful Improvements in Lacing-Hooks for Women's Shoes or the Like, of which the following is a specification.

My invention relates to improvements in 10 lacing-hooks for women's shoes and the like, the object of my invention being to provide an improved form of lacing-hook which shall be particularly adapted for use with women's shoes.

15 Heretofore the lacing-hook commonly used in the upper portion of men's shoes has been found to be inapplicable for women's shoes on account of the hook portion thereof catching and tearing the skirt of the wearer. Lacing-hooks therefore are not commonly used or indeed not used at all for women's shoes, notwithstanding their convenience in saving 20 time and labor in lacing the shoe.

The object of my invention is to provide a 25 new form of lacing-hook which can be applied to women's shoes without danger of catching or tearing the garment of the wearer.

My invention therefore resides in the novel 30 construction, combination, and arrangement 30 of parts for the above ends hereinafter fully specified, and particularly pointed out in the claim.

Referring to the drawings, Figure 1 is a 35 perspective view of a shoe furnished with my improved lacing-hooks. Fig. 2 is an enlarged view of a portion of the edge of the upper, showing one of said lacing-hooks in position thereon. Fig. 3 is a perspective view of a 40 right-side hook detached. Fig. 4 is a similar view of a left-side hook.

Referring to the drawings, 1 represents a shoe, and 2 the upper thereof. At the margins of said upper at the upper portion thereof are secured my improved lacing-hooks 3. 45 Each hook comprises an eye portion 4, by which it is riveted or clamped in the margin of the upper, and a hook portion extending from said eye portion. For this purpose the eye 4 is formed with a flange 10, which is 50 adapted to rest snugly against the margin of the upper, and said flange has an extension

5 in its own plane directed toward the edge of the upper, said extension being gradually reduced in width. Said extension is then bent upward or substantially parallel with the 55 edge of the upper, but still in the same plane—namely, that of the flange 10—to form a hook 6, the outer edge of said hook 6 being preferably just within the line of stitching 7 of the margin of the upper. Finally it is again 60 bent in the same plane as that of the flange in a direction away from the edge of the upper to form a short tooth 8 at the end of the hook.

The portion 6 of the hook is substantially 65 of the width of an ordinary flat shoe-lace, while the tooth 8 of the hook extends a distance substantially equal to the thickness of such a shoe-lace. Therefore when the lace is passed around the hook there is substantially 70 no projection of the tooth 8 beyond the lace. In operation after the shoe-lace 9 has been passed through the eyes 11 in the lower portion of the upper it is then passed inside or underneath the hook 6 and then around 75 the edge of the same next to the eye portion thereof and over the upper surface of the hook 6 to the opposite edge of the upper. Here it is in like manner passed first below the hook 6, then around the edge of the same, and then 80 over the hook across the shoe to the opposite edge of the upper. Each half of the lace is passed around the hooks in the same manner, the two halves crossing each other until 85 the last pair of hooks is reached, when the laces are tied together in the usual manner.

It will be seen that on account of the hooks pointing upward it is impossible for the points thereof to catch the skirt of the wearer, and, moreover, the hook portions are all protected 90 from contact with the skirt by means of the shoe-lace passing over said hooks. Notwithstanding that the hooks point upward the laces cannot slip off the same on account of the inwardly-projecting teeth at the end of 95 the hooks.

It will be seen that the hooks for each shoe are made right and left side, those for the right side of the shoe being slightly different in shape from those on the left to correspond 100 with the position which they are to occupy.

I do not restrict this invention to its use

with shoes, as my improved hook may also be used with advantage in ladies' corsets, &c.

I claim—

A lacing-hook for shoes comprising an eye portion arranged to be clamped in the shoe-upper, said eye portion having a flange, said flange having a straight extension therefrom of uniform thickness therewith in the same plane toward the edge of the upper, said exten-
tension forming the first part of the hook, said hook being then bent upwardly or parallel with the edge of the upper, but in the plane of the flange and in a straight line for a distance equal to the width of a flat lace,

and then bent outwardly at a sharp angle also 15 in the plane of the flange for a distance equal to the thickness of the lace to form a tooth, the whole hook thus formed being of uniform thickness with the flange, substantially as described. 20

In witness whereof I have hereunto set my hand in the presence of two subscribing witnesses.

N. H. CLARK.
